MATRIX ASSEMBLER LEVER MECHANISM

John William Powers, Burlington, Vt., assignor
to Free Press Association, Burlington, Vt., a
corporation of Vermont

Application September 16, 1944, Serial No. 554,469

8 Claims. (Cl. 199—27)

This invention relates generally to type-casting machines which cast a full line of type on one body, such as the Linotype, Linograph, and Intertype machines and more particularly to an attachment mechanism for such machines for pushing the last matrix assembled in a line of matrices inside of the assembling elevator gate pawls preparatory to their transfer to the delivery channel.

Such matrices with spacers are normally released from a supply magazine at the top of the machine, pass onto an endless belt and down guides to be assembled by a star wheel on the spaced bars of an assembling elevator, the assembled line then being raised to a delivery channel.

Machines of this general type are subject to frequent jamming of the apparatus due to the failure of the last matrix to be assembled to remain within the gate pawls of the elevator. This is especially troublesome when setting matrices on the assembled duplex rail which raises the matrices above the light face position in the assembling elevator and places them where they are cast in an italic or bold face.

This failure caused the matrix to protrude from the assembling elevator so as to be caught under the assembler chute finger, preventing the assembling elevator from rising and causing the already-assembled matrices and space bands in the assembling elevator to spill out on the floor. Such spilled matrices must be recovered and run back in the machine before the "down" machine can resume production. In the case of manually operated machines, it is necessary that the operator physically push the protruding matrix or matrices within the assembling elevator gate pawls and hold them in place until the assembling elevator is safely raised.

It is, accordingly, the chief object of the present invention to provide a mechanism susceptible of ready attachment to type-setting machines of the type described, which obviates the above difficulties whether the type-setting machine is operated manually, electrically, or mechanically. Examples of such are the Linotype, Intertype, and Linograph machines which produce metal slugs of varied widths and lengths, and type of different style faces from brass matrices or moulds.

It is another important object of the present invention to provide an attachment for type-setting machines which will ensure that the last descending matrix or matrices being conveyed by the usual endless assembler belt to the assembler star wheel, will be secured within the assembling elevator gate pawls and remain there in

an upright position with the other assembled matrices until the assembling elevator is raised to a given point.

It is a further object of the present invention to provide a matrix assembler lever mechanism which will positively prevent the jamming of matrices about the elevator gate pawls and which is so constructed as to remain unharmed in the event the machine being operated should jam from some other cause.

Another object of the present invention is to provide a matrix assembler lever mechanism for type-setting machines which will assist the action of the star assembler wheel and retain the matrices within the elevator gate pawls and which will be simply but ruggedly constructed so as to have long life without requiring frequent adjustments.

Other objects and advantages of the present invention will become apparent during the course of the following description.

In the drawings I have shown one embodiment of my invention.

In this showing

25 Figure 1 is a fragmentary front elevation of a typesetting machine equipped with the present invention;

Figure 2 is a fragmentary front elevation to an enlarged scale of the matrix assembler lever and its associated parts;

Figure 3 is a side elevation thereof;

Figure 4 is a plan view to an enlarged scale of the matrix push bar comprising a part of the present invention, and

35 Figure 5 is an exploded view of certain of the parts associated with the matrix assembler lever.

Referring now to the drawings:

Numeral 10 designates an endless belt by which the matrices 14 are fed onto rails 16 having

40 springs 17 for delivery to a conventional star assembler wheel 18 for assembly within the rails

20 of the elevator 22. The matrices 14 are fed successively to the star wheel 18 until the elevator

45 contains a complete line of type or portion thereof at which time the elevator is automatically raised to the transfer channel. The present invention insures that the last matrices are prevented from falling outwardly of the elevator gate

50 pawls 24 by holding them in their normal upright positions until the elevator is safely raised. The elevator side rails 20 may bear type scales 23

suitably fastened thereto. A plurality of bored brackets 25 formed integrally with the sides of

55 the elevator 22 receive (Figure 1) a horizontally

extending cam follower arm 26 which is provided at its opposite end with a headed roller bearing 30 suitably mounted therein. A cam lever 34 is provided with a slot 35 having a bend as at 37 to receive the roller bearing 30 and is pivoted to the machine frame by means of a bolt 36 and secured thereto by a nut 38. An angular matrix push bar lever 40 is also pivotally mounted on the bolt 36, extends upwardly and is provided in its upper end with an open slot 42. An apertured lug 44 is formed integral with the rear edge of the push bar lever 40.

The push bar lever 40 is directly connected to the cam lever 34 by means of a pin 46 one end of which is screw-threaded into the aperture of the lug 44 and its other end is received in the open slot 48 of a yoke member 50 which is pivotally mounted within an arcuate cut-out portion 52 formed in the rear edge of the cam lever 34. The portions of the pin 46 intermediate its ends are of greater diameter in order that it may act as a spacing collar between levers 34 and 40. The end of the pin 46 is retained in the slot 48 of yoke 50 by means of a leaf spring 54 which is provided with a slot 56 at its lower end for receiving the yoke 50, the fingers 58 which form the slot 56 bearing on and retaining the end of the pin 46 in the slot 48 as shown (Figure 2). The leaf spring 54 is suitably fastened to the rear edge of the cam lever 34 by means of screws, etc.

A matrix push bar 60 which is of flat rectangular shape and provided with an elongated slot 62 is supported intermediate its length in an apertured block 64 and at its right or lower end (Figures 1 and 2) by a pin 65 which retains it in its position in the slot of the matrix push bar lever 40.

A brass roller 66 is supported by a pin in the opposite end of the push bar 60 and is the means by which a matrix is pushed in and held within the elevator gate pawls 24 without injury or scratching thereof.

Although the operation of the matrix assembler lever mechanism is believed to be apparent, such operation and the functions of the various parts will now be described.

As seen in Figure 2, the cam lever 34 is in its at-rest position and the elevator 22 and the cam-follower arm 26 are at their lower limit of movement so that the roller bearing 30 is at the bottom of the cam lever slot 35. The cam lever 34, upon upward movement of the elevator 22 and the arm 26, and the resulting pressure of the roller bearing 30 on the upper edge of the short portion of the slot 35, is rotated counterclockwise upon the pivot bolt 36 so as to be in a vertical position when the roller bearing 30 rounds the bend 37 of the slot 35. Obviously, this rotary movement of cam lever 34 is coincidental with the initial upward movement of the elevator and after the bearing has passed the angle 37 of the slot 35, the lever 34 is merely maintained in a vertical position while the elevator moves up to the delivery channel and back downwardly until the roller bearing again reaches the bend 37 to now force the lever 34 to rotate in a clockwise direction back to the position shown in Figure 2.

Due to the direct connection between the cam lever 34 and the matrix push bar lever 40, the latter pivots simultaneously about the bolt 36 to slide the matrix push bar 60 angularly upwardly through the apertured block 64 so that the brass roller 66 moves from the at-rest position beneath

the assembler chute rails 16 to the dotted line position shown.

As shown in Figure 1, the elevator 22 has commenced its upward movement and a single matrix 14 is shown as projecting outwardly from the elevator gate pawls 24. Coincidental with the upward movement of the elevator, the matrix push bar 60 has moved upwardly to the left so that its brass roller 66 contacts the projecting matrix 14 as shown. It will be readily apparent that further upward movement of the elevator 22 and its arm 26 will rotate the cam lever 34 to its vertical position and slide the matrix push bar roller 66 to push the matrix 14 back within the elevator gate pawls 24 to permit the elevator to be safely raised without interference from the bar 60 itself.

Obviously, lowering of the elevator effects a return of the cam lever 34 and matrix push bar lever 40 to the at-rest position shown in Figure 2, the roller 66 of the push bar 60 being withdrawn under the assembler chute rails so as not to interfere with the assembly of the next line of type in the elevator.

In the event of the jamming of the mechanism from a cause other than accidental displacement of the matrix 14, the leaf spring 54 will take up the relative motion between the cam lever 34 and matrix push bar lever 40 supporting the matrix push bar 60 to prevent injury to the latter or any of its associated parts. This is an important feature of the present invention.

Accordingly, it will be apparent that the present invention constitutes an improved attachment for type-setting machines which is positively operated by motion of the elevator and is not dependent upon spring means for actuation. The mechanism may be readily attached directly to type-setting machines whether automatically or manually operated and is not dependent upon working parts such as a teletype-setter unit for any action.

This novel attachment for type-setting machines is readily adaptable to all types. Although the elevator gate pawls differ in length on the various types of machines, the matrix push bar of the present invention will function with all and the bar will enter within the elevator as far as permitted by the last matrix assembled.

The importance of the mechanism comprising the present invention as an attachment for type-setting machines of all types will be readily apparent. Its use not only definitely prevents the jamming of the elevator by the matrices, but causes the latter to assemble as true in the bold or italic position as in the light face position. Moreover, the renewing or replacement of the star wheel and assembler gate pawls is required much less frequently inasmuch as the matrix push bar 60 compensates for the wear of these parts. When once applied to type-casting machines, aside from the conventional adjustments, there is no changing of adjustments whether the line of matrices are to be set in a short or long measure or different lengths of ems.

It is to be understood that the form of the invention herewith shown and described is to be taken as a preferred example of the same and that various changes in the shape, size, and arrangement of parts may be resorted to without departing from the spirit of the invention or the scope of the subjoined claims.

I claim:

1. A mechanism for a type-setting machine of the type wherein a complete line of matrices are assembled in an elevator preparatory to their transfer to a delivery channel, comprising an apertured support mounted on said machine, a matrix push bar extending through said aperture and supported therein intermediate its length, a lever pivotally mounted on said machine and supporting one end of said bar, and means operated by vertical movement of the elevator to effect partial rotation of said lever to reciprocate said bar and push the last matrix to be assembled within said elevator, said means comprising a second lever pivotally mounted on said machine and coupled with said first lever, and a rod fixed to said elevator and having a sliding connection with said second lever.

2. A mechanism for a type-setting machine of the type wherein a complete line of matrices are assembled in an elevator preparatory to their transfer to a delivery channel, comprising an apertured support mounted on the machine, a matrix push bar extending through said aperture and supported therein intermediate its length, a lever pivotally mounted on said machine and supporting one end of said bar, a second lever having a slot therein pivotally mounted on said machine and coupled with said first lever, a rod fixed to said elevator and having operative engagement with said second lever and a bearing pin mounted on said rod and arranged for sliding movement within said slot to effect partial rotary movement of said levers and reciprocation of said push bar upon vertical movement of said elevator.

3. A mechanism for a type-setting machine of the type wherein a complete line of matrices are assembled in an elevator preparatory to their transfer to a delivery channel comprising an apertured support mounted on said machine, a matrix push bar extending through said aperture and supported therein intermediate its length, a lever pivotally mounted on said machine and supporting one end of said bar, a second lever having a slot therein pivotally mounted on said machine, a shouldered pin connecting and spacing said levers, a rod fixed to said elevator, and a bearing pin mounted on said rod for engagement within said slot to effect partial rotary movement of said levers and reciprocation of said bar upon vertical movement of said elevator to push a matrix therewithin.

4. A mechanism for a type-setting machine of the type wherein a complete line of matrices are assembled in an elevator preparatory to their transfer to a delivery channel, comprising an apertured support mounted on said machine, a matrix push bar extending through said aperture and supported therein intermediate its length, a lever pivotally mounted on said machine and supporting one end of said bar, a second lever pivotally mounted on said machine and coupled with said first lever, and means mounted on said elevator and slidably connected with said second lever to effect partial rotary movement of the levers and reciprocation of the bar upon vertical movement of said elevator to push a matrix therewithin.

5. A mechanism for a type-setting machine of the type wherein a complete line of matrices are assembled in an elevator preparatory to their

transfer to a delivery channel, comprising an apertured support mounted on said machine, a matrix push bar extending through said aperture and supported therein intermediate its length, a lever pivotally mounted on said machine and supporting one end of said bar, a second lever pivotally mounted on said machine and having a pin connection with said first lever, means mounted on said elevator and operatively connected with said second lever to effect rotary movement of the levers and reciprocation of the bar upon movement of said elevator to push a matrix therewithin, said second lever being provided with a pivotal yoke having an open, pin-receiving slot therein, and a bifurcated spring member mounted on said second lever to straddle said yoke and retain one end of said pin therein.

20 6. A mechanism for a type-setting machine of the type wherein a complete line of matrices are assembled in an elevator preparatory to their transfer to a delivery channel comprising a support mounted on the machine adjacent the elevator, a matrix push bar arranged for reciprocal movement on said support, coupled means pivotally mounted on the machine and supporting one end of said bar, and a rod mounted on the elevator and slidably connected with said means to effect reciprocation of said bar upon vertical movement of the elevator to push a matrix therewithin.

25 7. A mechanism for a type-setting machine of the type wherein a complete line of matrices are assembled in an elevator preparatory to their transfer to a delivery channel, comprising an apertured support mounted on the machine, a matrix push bar extending through said aperture and supported therein intermediate its length, a lever pivotally mounted on said machine and supporting one end of said bar, a second lever having a slot therein pivotally mounted on said machine and coupled with said first lever, a rod fixed to said elevator and having sliding engagement with said second lever and a bearing pin mounted on said rod and arranged for sliding movement within said slot to effect rotary movement of said levers and reciprocation of said push bar upon vertical movement of said elevator, and means mounted on said second lever constructed and arranged to permit uncoupling of said levers upon substantial relative movement therebetween.

30 8. A mechanism for a type-setting machine of the type wherein a complete line of matrices are assembled in an elevator preparatory to their transfer to a delivery channel, comprising an apertured support mounted on said machine, a matrix push bar extending through said aperture and supported therein intermediate its length, a lever pivotally mounted on said machine and supporting one end of said bar, a second lever pivotally mounted on said machine and coupled with said first lever, and means mounted on said elevator and slidably connected with said second lever to effect partial rotary movement of the levers, reciprocation of the bar upon movement of said elevator to push a matrix therewithin, and means mounted on said second lever constructed and arranged to permit uncoupling of said levers upon substantial relative movement therebetween.
